UNITED STATES PATENT OFFICE.

LESTER B. BROWN AND JOSIAH H. NORRIS, OF BRADFORD, PA.

FURNACE.

SPECIFICATION forming part of Letters Patent No. 249,891, dated November 22, 1881.

Application filed July 21, 1881. (No model.)

To all whom it may concern:

Be it known that we, LESTER B. BROWN and JOSIAH H. NORRIS, of Bradford, McKean county, Pennsylvania, have invented a new 5 and useful Improvement in Furnaces; and we do hereby declare that the following is a full, clear, and exact description thereof, reference being had to the accompanying drawings, and the letters or figures of reference marked 10 thereon.

Our invention relates to furnaces.

Manufacturers and others connected with the working of metal have heretofore been under great expense in replacing the fronts that 15 have been burned out by the excessive heat generated by the blast.

The object of our invention is to produce means which will remedy that defect and also produce results that will render the furnace 20 more useful, and at the same time protect the workmen from the great heat; and to these ends our invention consists of a new and improved front, through which a current of cold water is constantly passing, and in other de- 25 vices, which will hereinafter be explained, for producing the results above referred to.

In the drawings, Figure 1 represents a perspective view of our improved fronts joined together by means of water-connections and 30 side D; Fig. 2, a transverse section on line x x, Fig. 3; Fig. 4, a longitudinal section on line y y, Fig. 2; Fig. 4, a face view of one of the fronts, showing the manner of attaching the door; Fig. 5, a perspective view of the base H; Fig. 6, a perspective view of the conformator, and Fig. 7 an elevation of our ash-pipe.

The furnace here represented has two fronts; but that form is not considered material to carry out the purpose of our invention, as it is 40 obvious that our improved front could be used upon a forge having a single supply-opening as well as upon the kind shown. We prefer, however, to show the invention applied to a furnace having two fronts, for the reason that 45 peculiarities in circulating the water can be described and shown.

A represents the base; C C', the fronts; D D, the sides above the base; E, arched top; F, tuyeres; G, the ash-pit, having extension 50 G'; H, the base for supporting the fire-brick, and K the conformator.

The fronts C C' are made hollow to allow a current of water to flow therethrough. The water may be supplied from any desired source, and is passed to the fronts by means of pipes. 55 Each front may have a distinct supply-pipe, or they may be joined, as shown in the drawings. The supply-pipes L enter the fronts at the side and near the bottom. The water flows upwardly over the arched doors and out 60 at the tops through pipes N N'; or, if desired, pipes N N' may be dispensed with, and a T-union placed midway between the fronts and on pipe P, that connects the fronts together. A pipe, P', without a union, is placed upon the 65 side opposite to pipe P.

If desired, the connection L' and pipe N' may be dispensed with and a single supply-pipe, L, used. If this form be used, the water will enter at the lower end of front C, pass over the 70 arched door, out through pipe P into front C', over the arched door to the pipe P', placed near the tops of the fronts, back again to front C, and out by means of pipe N, after the water has crossed the upper part of the chamber in 75 front C. By such a circulation it can readily be seen that as the water becomes more heated it will have an ascending passage, thus facilitating the circulation.

In the crown of each front is placed a steam 80 or vapor escape pipe, S, to prevent the pressure from becoming too great.

It is evident that the cold water circulating through the fronts will prevent them from burning out, and also protect the workman from the 85 heat. This last is considered one of the best features of the invention, as it enables the workmen to stand to their work without suffering from the great heat. The workman will thus be enabled to do his work in a more com- 90 fortable manner and the employer be a gainer, for the reason that the workman can do more work when he labors under fewer difficulties. The ends of these fronts are connected by side pieces, D D, and the whole seated upon a 95 base, A.

The base A rests upon the floor, and is provided with side pieces, A', which extend upwardly to the same height as the bottom of plates D. The base H rests upon walls A'' 100 and supports the walls I I. The space between the walls I I and side pieces, A', is filled with

clay. The space between the walls I I form an oblong chamber, T, which serves as an extension for the fire-chamber surrounded by parts C C' and D D. Beneath this chamber, 5 and separated therefrom by a base, H, is an ash-pit, G. An oblong opening in base H admits the ashes and clinkers to the ash-pit, and they are taken therefrom through passage G'. This passage may be formed in any suitable 10 manner. A pipe having one end cut at a long or acute angle may be used. If such a pipe be used, the upper side of the cut part should be placed immediately below the oblong opening. To prevent the blast from finding its way 15 out via this opening, a suitable door, G'', is placed at the outer end. Upon the base H a wall of fire-brick is built upon each side and extends upwardly nearly to the top of the fronts C C'. Between the walls I I and the sides D 20 D, and between the spaces in the base, is placed clay, M, or other suitable substance, to prevent the heat from radiating.

A brick arch may be placed upon walls I I and clay packed over it; but one made of 25 coal is preferred, for the reason that it generates the heat much better than the ordinary means. The method of forming this arch is very simple. The slightly-tapering conformator K is placed through the doorways, as shown 30 in Fig. 3, and a fire started in the pit of the furnace. While this fire is burning, coal slightly dampened is packed down upon the conformator and the sides D. The heat rising from the furnace heats the conformator K and the coal 35 next to it, and forms the latter into coke. When the coal has become sufficiently coked the conformator is drawn out, thus leaving the coked surface to stand the action of the flames and heat. If the coal immediately over the 40 fire is kept in a damp state, the coal will be preserved for a long time, and when it does burn out the burnt portion can be replaced at little cost.

Many advantages over the ordinary forge are 45 gained by using this arch and the ash-pit. Among other advantages is the saving of fuel. Only one-quarter of the amount of fuel commonly used in other furnaces or forges is necessary in ours; and, further, the fire can be 50 kept up for weeks, whereas in the ordinary construction the fire must be made every morning, as there are no means provided for taking out the ashes and clinkers from the bottom, as in our device, but, on the contrary, the workmen are compelled to let the fire die out every 55 evening, so that they can remove the débris in the forge. This removal is accomplished by taking the ashes, &c., out by way of the doorway, above the bottom of the pit, in small dribbles, by means of a small shovel, whereas in our 60 device any suitable device is run into the passage G', and the ashes and clinkers at the bottom of the fire removed by dragging.

As a further protection to the workman, and 65 also to save expense in replacing doors burned out, a door, C'', made hollow in the same man-

ner as the fronts, is placed upon the forge. To hold the door in place, lugs c c are cast on each side of the doorway and near the bottom thereof. These lugs are angular in form, and the 70 free arms point toward each other. The door is provided with flexible pipes c' c'', which are connected with a supply-pipe, c³, and exit-pipe c⁴. The object in providing flexible pipe c' c'' is to give the door free play, which would not 75 be the case if the pipes were of a rigid material. A lever, c⁵, having a weight, c⁶, is used to operate the door.

The tuyeres F shown in the drawings are nothing more than ordinary pipes. In practice, however, tuyeres that are commonly used in this class of devices will be substituted. In practice the tuyeres will be above the ash-pit, and if the base H be used a slot, h, will be made 80 therein to allow the tuyere to pass through. 85

We are aware that it is not new to provide forges with hollow fronts and connect them together with pipes provided with means for supplying the fronts with and relieving them of water, and we make no claim therefor; but 90 we are not aware that fronts so connected have ever been supplied with means for relieving them of the pressure caused by steam generated by the heat of the furnace. If they be not so relieved, the steam will prevent the 95 water from entering the front, unless the water is forced in under great pressure, and even then the cold water is liable to burst the front, if the latter be very hot. We obviate these difficulties by placing a pipe, S, in the crown 100 of the front, so as to relieve the latter at the point where the pressure is greatest.

What we claim as new is—

1. A furnace having a hollow front and provided with suitable connections for supplying 105 it with a continuous current of cold water, for the purposes set forth, and a steam-escape pipe in the crown, and all combined and arranged substantially as described.

2. A furnace having hollow fronts connected 110 together by means of pipes, substantially as described, and combined with suitable means for supplying them with and relieving them from water, and a steam-escape pipe in the crown 115 of each front, and all combined and arranged substantially as set forth.

3. A furnace having hollow fronts connected 120 together by means of sides D, and having connections for supplying a current of cold water thereto, and a steam-escape pipe in the crown 125 of each front, and all combined and arranged substantially as set forth, a fire-chamber having an arched top and a metal bottom, and an ash-pit below the bottom, and having a passage for the removal of the ashes and clinkers, all combined and arranged substantially 130 as described.

4. A furnace having hollow fronts connected 130 together by means of sides D, and having connections for supplying a current of cold water thereto, and a steam-escape pipe in the crown of each front, and all combined and arranged

substantially as set forth, and an arched top formed of coal, all combined and arranged substantially as described.

5. In a furnace, a hollow door operated in the manner substantially as described, and having flexible pipes connected with means for supplying and relieving the door of water, in combination with a front having means for holding the door in place, substantially as de-
10 scribed.

In testimony that we claim the foregoing we have hereunto set our hands this 29th day of June, 1881.

LESTER B. BROWN.
JOSIAH H. NORRIS.
